UNITED STATES PATENT OFFICE

2,460,695

SENSITIVE SWITCH ACTUATOR

Mark M. Hennessy, Milwaukee, Wis., assignor to
 Durant Manufacturing Co., Milwaukee, Wis., a
 corporation of Wisconsin

Application August 31, 1946, Serial No. 694,224

4 Claims. (Cl. 74—96)

1

The present invention relates in general to improved mechanism for transmitting motion from one article or element to another, and relates more specifically to an improved assemblage for effecting periodic actuation of relatively frail and sensitive electric switches or the like.

The principal object of my invention is to provide an improved actuator for relatively frail and sensitive electric switches and the like, which is simple and durable in construction and reliable in operation, and which is moreover flexible in its adaptations.

When utilizing sensitive snap-action electric switches of the type wherein the movable contact is carried by a spring metal arm and is snapped from one limiting position into another by means of one or more integral cantilever leaf springs when plunger pressure is applied to the carrier arm near its anchored end, it is frequently imperative that the push button or actuating plunger be quickly and positively pressed and released. This is especially true when such switches are used to control the operation of counters for registering a succession of moving articles, machine performances, or other events, and in such cases the mechanism for actuating the switch operating plunger must not only be positive in action and susceptible of adjustment to meet varying conditions, but it must also be adapted for actuation with a relatively light touch in cases where the movements or articles being counted are too light to actuate a mechanical counter direct. The switch actuating mechanism must also be effectively operable while disposed in any position, and should be applicable in cases where overtravel or time elements are required after each performance of a machine or happening of an event.

It is therefore a more specific object of the present invention to provide an improved actuating device for sensitive electrical snap switches or the like, which meets all of the above mentioned requirements and conditions, and which is adapted to be utilized for diverse purposes.

Another specific object of this invention is to provide an improved motion transmitter for transferring periodic or successive movements of a machine or series of articles to a control device such as a snap switch, in a most effective manner and with the exertion of minimum effort.

A further specific object of the invention is to provide an improved sensitive switch actuator which may be operated in any desired position, and which will also automatically compensate for overtravel or time elements involved in the

2

operation of the devices with which the actuator is associated.

Still another specific object of my invention is to provide simplified mechanism for imparting successive clear-cut and distinct operating movements to the push button or actuating plunger of a snap actuated element such as an electric switch contact carrier arm or the like, which may be manufactured and sold at moderate cost for diverse uses.

An additional specific object of this invention is to provide an improved switch actuator having an oscillatory operating arm cooperable with a pivot shaft, lever, and springs, in such a manner, that the arm will be quickly returned to neutral or inactive position whenever the arm is released after having been swung in either direction about the pivot shaft axis.

These and other specific objects and advantages of the improvement will be apparent from the following detailed description.

A clear conception of the features constituting my present invention, and of the mode of constructing and utilizing a typical embodiment thereof, may be had by referring to the drawing accompanying and forming a part of this specification in which like reference characters designate the same or similar parts in the various views.

30 Fig. 1 is a front view of a typical snap switch actuating mechanism, having a portion of the closure cover broken away and showing the actuating arm in neutral or inactive position;

Fig. 2 is a transverse section through the assemblage of Fig. 1 taken along the irregular line 2—2 and looking in the direction of the arrows; and

Fig. 3 is an enlarged part sectional fragmentary view of the upper portion of the actuator, showing the operating arm in action in both solid and dot-and-dash lines.

While the invention has been shown and described as being advantageously applicable to sensitive electric snap switches of a particular type, it is not my desire or intention to unnecessarily limit the scope or to restrict the utility of the improved features by virtue of this specific embodiment.

Referring to the drawing, the improved switch actuating assemblage shown therein, comprises in general a main housing or casing 5 having a removable closure cover 6; a sensitive snap switch 7 mounted centrally within the casing 5 and being provided with a movable contact carrier arm 8 and with a push button or plunger 9 for apply-

ing actuating pressure to the arm 8; a leaf spring 10 anchored at one end to the switch housing and having its medial portion cooperable with the switch plunger 9 while its opposite end 11 is freely swingable; a rigid lever 12 swingable about a fixed pivot pin 14 and coacting remote from this pivot with the leaf spring end 11 and with one end of a helical compression spring 15 the opposite end of which is confined with a socket 16 formed in the main casing 5; an oscillatory shaft 17 journalled in a bearing 18 formed in the casing 5 and having its inner end provided with a transverse slot or recess 19 the flat bottom surface 20 of which is adapted to coact with the adjacent flat surface of the lever 12, while its outer end projects outwardly of the casing 5 and has a collar 21 clamped thereto by a set screw 22; and an operating lever arm 24 adjustably associated with the collar 21 and shaft 17.

The main casing 5 may be provided with supporting lugs 25 and with an opening 26 for accommodating the electrical current conductors for the switch 7, and the closure cover 6 is detachably secured to the casing by screws 27. The snap switch 7 which is fastened within the main casing 5 by means of screws 28, is of a well known type having the contact carrier arm 8 for the movable contact 29 anchored to the switch base near the push button or plunger 9, so that slight pressure applied to the protruding end of the plunger will cause the movable contact 29 to snap from one extreme position to the other, whereas release of the plunger will automatically cause the contact 29 to return to its initial position. The switch 7 is also provided with a removable cap 30 for normally concealing the delicate parts thereof, and the leaf spring 10 which coacts with the plunger 9, may be held in proper position by a pin 31 carried by a yoke 32 firmly secured to the switch cap 30 in any suitable manner.

The lever 12 which is swingable upon the fulcrum pin 14, may be formed of flat bar stock, and has plane parallel surfaces on its opposite sides, one of which is adapted to be slidably engaged by the leaf spring end 11, and the other of which is engageable with the flat recess surface 20 whenever the lever 12 is in neutral position. The end of the lever 12 remote from the pivot pin 14 is provided with notches 34 within which the adjacent end of the coil spring 15 is seated, and the opposite end of this compression spring is seated within the socket 16 and is removably confined therein by means of a washer 35 and a screw 36. The oscillatory shaft 17 which is journalled in the frame bearing 18, is prevented from shifting axially by means of inner and outer collars 37, 38 respectively, secured to the shaft by pins 39, 40, and the inner pin 39 projects outwardly beyond the periphery of its collar 37 and is engageable with two stop pins 42, 43 secured to the casing 5 and disposed in the path of swing of the protruding end of the pin 39.

The recess 19 formed in the shaft 17 and through which the bar lever 12 extends, is preferably of such width that the lever is freely movable therein, and of such depth that it extends inwardly beyond the central shaft axis. As previously indicated, the bottom surface 20 of the recess 19 is plane and of considerable length so as to rather firmly and positively hold the shaft 17 in neutral position when the surface 20 engages the adjacent plane surface of the lever 12, but the opposite ends of the recess surface 20 may be rounded as shown in order to prevent excessive wear on the shaft 17 and lever 12. The collar 21

may be secured in various positions along the protruding end of the shaft 17 with the aid of the set screw 22; and the actuating arm 24 has a flattened portion 44 cooperable with the adjacent 5 shaft periphery and slidable within the collar 21, thereby preventing turning of the arm 24 about its own axis while permitting longitudinal adjustment of the arm relative to the collar, see Fig. 2. The set screw 22 which clamps the collar 22 to the shaft 17, also serves to clamp the arm 24 in various positions of adjustment; and while all parts of the mechanism are of sturdy construction, they are relatively light in order to minimize the effects of gravity thereon.

When the improved switch actuator has been properly constructed and assembled, it may be disposed in any desired position and utilized for diverse purposes, such as registering the count of an electrically actuated counter of articles which are too light and not sufficiently massive to actuate an ordinary mechanical counter. It may also be utilized to count a succession of articles such as bottles, cans, jars, boxes, and the like in commodity packing plants where remote registry of production is desired, and in cases where sensitive limit switches are used to control various electrical functions requiring overtravel or time elements in connection with machine operations. The arm 24 when in neutral position as shown in Fig. 1, permits the recess surface 20 to contact the adjacent plane surface of the lever 12 under the influence of the springs 10, 15; and whenever the arm 24 is swung in either direction as shown in solid and dot-and-dash lines in Fig. 3, the cam portion of the shaft 17 at the recess 19, will swing the lever 12 toward the switch 7 thereby compressing the coil spring 15 and operating the switch. Release of actuating pressure on the arm 24, causes the springs 10, 15 to quickly return the arm 24 to neutral position where it is retained by the flat surface 20 of the recess 19, and the protruding end of the pin 39 is engageable with the stop pins 42, 43 so as to limit the oscillatory motion of the arm 24 in either direction.

From the foregoing detailed description, it should be apparent that the present invention provides an improved actuator especially adapted for use in actuating sensitive electrical snap switches, which besides being light but durable 50 in construction, is positive in action and is also flexible in its adaptations and uses. The improved switch actuating mechanism is operable with a very light touch and in any desired position, and the flat surface 20 of the pivot shaft 17 cooperates with the lever return spring 15 to insure rapid and automatic return of the arm 24 to neutral position whenever the latter is released. The arm 24 may be swung in either direction, and adjusted to any desired length and to various positions along the shaft 17, so as to accommodate different working conditions; and the pin 39 cooperating with the stop pins 42, 43 prevents the shaft 17 from revolving completely about its axis. All of the relatively light but strong parts of the assemblage are adequately protected against tampering and damage by the housing casing 5, but these enclosed parts are still readily accessible for inspection and adjustment. The adjustable oscillatory arm 17 has also proven useful in compensating for overtravel and time elements existing or required in connection with certain applications of the switch 7, and oscillation of the lever 24 in either direction may either make or break the electric circuit, thus making the assemblage exceedingly flexible in its adapta-

tions. The improved snap switch actuator has proven highly satisfactory and successful in actual use, and may be manufactured at moderate cost in various sizes and for many different uses.

It should be understood that it is not desired to limit this invention to the exact details of construction or to the precise mode of operation and uses, herein shown and described, for various modifications within the scope of the appended claims may occur to persons skilled in the art; and specific terms used herein should also be given the broadest possible interpretation or meaning, consistent with the prior art.

I claim:

1. A switch actuator comprising, a switch housing casing, a rigid lever pivotally suspended within said casing in spaced relation to the switch, a leaf spring interposed between said lever and the actuating plunger of the switch, the free end of said spring remote from said plunger slidably engaging one side of the swinging end of said lever, an oscillatory shaft journalled in said casing transversely of said lever and having a transverse recess provided with a flat elongated bottom surface facing and cooperable with the opposite side of the swinging end of said lever to position the latter in neutral position, said recess being of greater depth than the length of the adjacent radius of the shaft, a stiffer second spring confined within said casing and coacting with said lever to constantly urge the same toward said shaft and recess bottom, and an arm projecting laterally of said shaft externally of said casing for oscillating the shaft.

2. A switch actuator comprising, a switch housing casing, a rigid lever pivotally suspended within said casing in spaced relation to the switch, a leaf spring interposed between said lever and the actuating plunger of the switch, the free end of said spring remote from said plunger slidably engaging one side of the swinging end of said lever, an oscillatory shaft journalled in said casing transversely of said lever and having a transverse recess provided with a flat elongated bottom surface facing and cooperable with the opposite side of the swinging end of said lever to position the latter in neutral position, said recess being of greater depth than the length of the adjacent radius of the shaft, a stiffer second spring confined within said casing and coacting with said lever to constantly urge the same toward said shaft and recess bottom, an arm projecting laterally of said shaft externally of said casing for oscillating the shaft, and means for effecting adjustment of said arm along said shaft and for varying the length of the arm.

3. A switch actuator comprising, a switch housing casing, a rigid lever pivotally suspended with-

in said casing in spaced relation to the switch, a leaf spring interposed between said lever and the actuating plunger of the switch, the free end of said spring remote from said plunger slidably engaging one side of the swinging end of said lever, an oscillatory shaft journalled in said casing transversely of said lever and having a transverse recess provided with a flat elongated bottom surface facing and cooperable with the opposite side of the swinging end of said lever to position the latter in neutral position, said recess being of greater depth than the length of the adjacent radius of the shaft, a stiffer second spring confined within said casing and coacting with said lever to constantly urge the same toward said shaft and recess bottom, an arm projecting laterally of said shaft externally of said casing for oscillating the shaft, and means within said casing for limiting the oscillatory movement and for preventing axial displacement of said shaft.

4. A switch actuator comprising, a switch housing casing, a rigid lever pivotally suspended within said casing in spaced relation to the switch, a leaf spring interposed between said lever and the actuating plunger of the switch, the free end of said spring remote from said plunger slidably engaging one side of the swinging end of said lever, an oscillatory shaft journalled in said casing transversely of said lever and having a transverse recess provided with a flat elongated bottom surface facing and cooperable with the opposite side of the swinging end of said lever to position the latter in neutral position, said recess being of greater depth than the length of the adjacent radius of the shaft, a stiffer second spring confined within said casing and coacting with said lever to constantly urge the same toward said shaft and recess bottom, an arm projecting laterally of said shaft externally of said casing for oscillating the shaft, a collar secured to said shaft within said casing by a pin projecting beyond the collar for preventing axial shifting of the shaft, and stop pins cooperable with said projecting pin to limit the oscillatory movement of said shaft.
